(57) CLAIM

I claim the ornamental design for a carry bag, as shown.

DESCRIPTION

FIG. 1 is a perspective view from the front, right side, and top of a carry bag showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top view thereof; and,
FIG. 7 is a bottom view thereof.
